UNITED STATES PATENT OFFICE.

CARLO FANELLA, OF ROME, ITALY.

MUSICAL APPLIANCE.

Application filed March 24, 1925, Serial No. 17,887, and in Italy March 27, 1924.

The invention relates to a musical appliance consisting in a device for using a syn-optical table indicating scales, arpeggios and other exercises. The said device comprises 5 a casing externally bearing said table, and internally containing rotatable discs with the particulars of musical exercises to be seen through openings in the table, furthermore a double slide with indicator serving 10 to point out the indications wanted.

The invention is illustrated by way of example in the accompanying drawings in which Fig. 1 shows an elevation of the device;

15 Figs. 2 and 3 show cross sections on lines 2-2 and 3-3 of Fig. 1;

Fig. 4 is a longitudinal section on line 4-4;

20 Fig. 5 illustrates the internal rotatable discs;

Fig. 6 illustrates the appliance connected with the music stand of the piano;

25 Fig. 7 illustrates a modification of the invention with the discs on a larger scale;

Fig. 8 shows the notations of the tonics and the small pinions handling the discs 30 from the front part of the device;

Fig. 9 shows a longitudinal section on line V-V of Figs. 7 and 8;

35 Fig. 10 illustrates the practical application of the appliance to the piano and orchestral music stand.

Fig. 11 is a view of the device attached to a music stand.

35 On the back of the device around pivots 2-2¹-2^{II}-2^{III} rotatable discs 4-5-6-7 are placed within corresponding recesses as illustrated in Figs. 5-7. The front wall of the casing is provided with openings 12- 40 13-14-15 and protected by a glass. The glass frame 9 serves as a bearing and guide for a slide with a longitudinally running index 10 within which a second slide is transversally movable.

45 The discs may be turned from the top side of the table or from the bottom side either from without where they project (Fig. 1) or from the front side by means of gears, as illustrated in Fig. 8—all of them bearing 50 besides the word "stop" the following legends:

Disc 4—major—minor—harmonic—melodic—mixed.

Disc 5—octave—third—sixth—tenth—octaves.

Disc 6—perfect major—perfect minor—

dominant seventh—diminished seventh—ninth.

Disc 7—fundamental—first inversion—second inversion—third inversion—fourth 60 inversion.

On the front face —8— there are traced two or four musical staffs in violin, bass clef, and so on. The number of staffs,—as the specification of the clef relating to the 65 exercises on the discs,—is variable according to the musical instrument played on.

The musical staffs are divided in sixteen fields of equal length and in each field there are progressively specified the single sharps 70 and flats with the notes of the corresponding tonalities, the major tones being in the upper part, and the minor tones in the lower part of the table.

In the intermediate space of the table between the openings there is the legend of the exercise to be performed namely: scale . . . with the distance of . . . tone of * arpeggio on the accord of . . . tone of *, the asterisk indicating the note and tone to 80 which the index has to be moved.

The device according to invention may be constructed as an integral part of the piano, as shown in Fig. 6, or is connected to the piano, as illustrated in a—b—c, Fig. 10. 85 When constructed for singing, or for other musical instruments than pianos, the device will be united to the music stand, as shown in Fig. 11.

The device may be of celluloid, ebonite, 90 aluminium, mother of pearl, ivory and the like, or in metal or any convenient material or composition.

Working of the device.

1. To find the tonics a look at the table is sufficient.

2. For the performance of the scales the index 10 has to be moved and stopped on a division of the table, whereupon the internal slide (11) is moved on the upper or lower part of the table and stopped on the staff, notes or note wanted; then the discs 4 and 5 are turned so that the tone and interval wanted appears in the openings 12-13. Should, for instance, the scale of G sharp major be performed with the interval of an octave, the fundamental note G will be fixed by means of the index, whereupon the disc 4 is so turned that the word "major" appears, and afterwards the disc 5 so 105 that the word "octave" also appears. 110

To perform the arpeggios the preceding discs used are covered with the word "stop"; then, after fixing, as already pointed out, the fundamental note, the two discs 6 and 7 are so turned that the sequence of the notes and the interval wanted appear in the openings 14 and 15. Should the arpeggio on the fundamental perfect major accord in the tonics of C major be performed, the note 10 of C major is fixed in the upper part of the table by means of the index, whereupon the disc 6 is so turned that the words "perfect major" appear, and then the disc 7 so that the word "fundamental" appears.

15 Any other exercise may be performed in a similar way.

In short, by means of the appliance according to the invention the fundamental note, the tonality, the interval for the 20 gamut of all the scales, the fundamental note, the sequence of the notes, tonics and interval of the principal arpeggios are indicated.

The device is capable of showing the indication of several hundreds of exercises to 25 be daily performed without the necessity of consulting any sheet of music.

Having now particularly described and ascertained my said invention and the manner in which the same is to be performed, 30 what I claim and desire to secure by Letters Patent is:

1. In a musical synoptical table and indicator serving to point clef, tonics, major or minor, for assisting in the performance 35 of exercises, the combination of a plurality of independently rotatable discs having legends thereon pertaining to tones, intervals of all the scales, inversions of arpeggios, and spaced superimposed casing members embracing the discs and provided with openings through which the legends on the discs may be seen, the face of the casing having a series of musical staffs indicating the sharps and flats with the notes of the corresponding tonics.

2. In a musical synoptical table and indicator serving to point clef, tonics, major or minor, for assisting in the performance 50 of exercises, the combination of a plurality of independently rotatable discs having legends thereon pertaining to tones, intervals of all the scales and inversions of arpeggios, spaced superimposed casing members embracing the discs and provided with 55 openings through which the legends on the discs may be seen, the face of the casing forming a table and having a series of musical staffs indicating the sharps and flats with the notes of the corresponding tonics, and an indicating slide movable

longitudinally over the face of the casing to any division of the table.

3. A musical table and indicator, as claimed in claim 2, including a second slide arranged in the indicator slide and adapted 65 to move transversely of the staffs to indicate major or minor keys.

4. In a musical synoptical table and indicator serving to point clef, tonics, major and minor, for assisting in the performance of 70 exercises, the combination of a plurality of independently mounted rotatable discs having legends thereon pertaining to tones, intervals of all the scales, inversions of arpeggios, spaced superimposed casing members 75 embracing the discs and having openings through which the legends on the discs may be seen, the face of the casing forming a table and having a series of musical staffs, one series above the other and indicating the 80 sharps and flats with the notes of the corresponding tonics, means for rotating each disc, a slide indicator movable over the staffs, and a second slide carried by the first slide and adapted to be moved over the lower 85 or upper staff.

5. In a musical synoptical table and indicator serving to point clef, tonics major or minor for assisting in the performance 90 of exercises, the combination of four rotatable discs spaced from each other and independently mounted, the discs respectively having printed on their surfaces, major, minor, harmonic, melodic and mixed, octave, 95 third, sixth, tenth and octaves, perfect major, perfect minor, dominant seventh, diminished seventh and ninth, and fundamental, first inversion, second inversion, third inversion, and fourth inversion, and a frame for the discs comprising a plate superimposed over the discs and having four 100 openings through which the legends on the discs may be seen, said plate having on its face four musical staffs according to the instrument used, one staff being arranged 105 above one other staff, the upper row indicating major and the lower row minor keys, a slide for the frame movable longitudinally thereof to indicate a bar of any clef, and a second slide in the first slide to move over 110 the upper clef or lower to indicate major or minor.

6. A musical device as claimed in claim 5, including means for attaching same to the musical instrument with which it is used, 115 substantially as described.

In testimony whereof I have hereunto signed my name.

Rome, 7th March, 1925.

CARLO FANELLA.
